UNITED STATES PATENT OFFICE

157,116

TRAILER LOCK

Arthur R. Adams, Glendale, and Burton L. Shannon, Pasadena, Calif., assignors to Adams Rite Manufacturing Company, Glendale, Calif., a corporation of California

Application August 16, 1948, Serial No. 148,128

Term of patent 14 years

(Cl. D50—7)

To all whom it may concern:

Be it known that we, Arthur R. Adams and Burton L. Shannon, citizens of the United States, residing at Glendale and Pasadena, respectively, in the county of Los Angeles and State of California, have invented a new, original, and ornamental Design for Trailer Lock, of which the following is a specification, reference being had to the accompanying drawing, forming part thereof.

Fig. 1 is a perspective view of a trailer lock, showing our new design.

Fig. 2 is a top view of the same.

Fig. 3 is one end view as seen from line 3—3.

Fig. 4 is the opposite end view as seen from line 4—4.

We claim:

The ornamental design for a trailer lock, as shown.

ARTHUR R. ADAMS.
BURTON L. SHANNON.
